MOTOR VEHICLE

Frederick M. Stewart, Los Gatos, Calif., assignor to
FMC Corporation, San Jose, Calif.

Filed July 24, 1972, Ser. No. 274,681

Term of patent 14 years

Int. Cl. D12—08

U.S. Cl. D12—99

FIG. 1

FIG. 2

FIG - 3

FIG 4

FIG. 5

FIG. 6

FIG-7

FIG. 8

FIG. 1 is a left front perspective view of a motor vehicle showing my new design;

FIG. 2 is a right front perspective view thereof;

FIG. 3 is a right rear perspective view thereof;

FIG. 4 is a left side elevational view thereof;

FIG. 5 is a right front perspective view of a motor vehicle showing a second embodiment of my new design;

FIG. 6 is a right rear perspective view thereof;

FIG. 7 is a right side elevational view thereof; and

FIG. 8 is a left side elevational view thereof.

The top of the motor vehicle is unornamented and follows the contour of the roof line shown in the drawings.

I claim:

The ornamental design for a motor vehicle, as shown and described.
